(57) **CLAIM**

We claim the ornamental design for a razor cartridge, as shown and described.

DESCRIPTION

FIG. 1 is a front perspective view of the razor cartridge.

FIG. 2 is a top view of the razor cartridge.

FIG. 3 is a front view of the razor cartridge.

FIG. 4 is a right hand side view of the razor cartridge, the left hand side view of the razor cartridge is a mirror image thereof.

FIG. 5 is a rear view of the razor cartridge; and,

FIG. 6 is a bottom view of the razor cartridge.

The broken lines immediately adjacent the shaded areas represent the bounds of the claim and all other broken lines are for illustrative purposes only. None of the broken lines form a part of the claimed design.
